UNITED STATES PATENT OFFICE.

HENRY T. McCARTHY, OF LOS ANGELES, CALIFORNIA.

SINK AND GARBAGE RECEPTACLE.

Application filed March 1, 1926. Serial No. 91,459.

My invention relates to a novel form of apparatus whereby the garbage accumulated in a dwelling may be quickly and easily disposed of without carrying the same from 5 the building, and more particularly relates to a specially constructed sink and a compartment in the dwelling associated therewith and accessible only from the exterior of said dwelling, means being provided for 10 ventilating said compartment, draining any fluids reaching the same, and effectively preventing any vermin or insects of all sorts from reaching the interior thereof, means being also provided for preventing the freezing 15 of the garbage in cold climates.

It accordingly is an object of my invention to provide a novel form of sink associated with a compartment accessible only from the exterior of the building, in which 20 compartment may be positioned a garbage receptacle to receive the garbage deposited in the sink, or in one or more compartments associated therewith, means being provided for automatically conveying the garbage to 25 the garbage receptacle, which means may be equipped with a closure of any preferred type, such as a rubber ball or a half-spherical member equipped with a counter balance of any preferred type, and if desired 30 with an operating means in the shape of a cord or chain operable in the vicinity of said sink, said closure being so constructed as to provide a water seal to effectively prevent any odor from the garbage reaching the 35 interior of the building.

It is also within the province of my invention to equip the usual sewer drain from the sink, provided with the usual trap, with a connection to the garbage conveying 40 means, so that any accumulation of water from the garbage may be drained off to the sewer, but still enough water remaining to afford a water seal.

It is also within the province of my invention to provide my novel form of sink 45 with a suitable means for packing a garbage receptacle or receptacles associated therewith to prevent any odors from the garbage reaching the room in which the sink is positioned, which means may take the form of a suitable gasket associated with a set of spacing and positioning flanges.

A further object of my invention is to 50 provide a novel form of apparatus which is simple in character, easy and inexpensive to construct, composed of a minimum num-

ber of parts, thoroughly effective and efficient in operation, and one which will thoroughly and reliably effect the objects intended. 60

Further objects and advantages of my invention will become more apparent as the description thereof proceeds.

Reference is had to the accompanying drawings, in which similar reference characters denote similar parts. In the drawings, 65

Fig. 1 is a fragmentary exterior view of a building partly broken away to disclose the sink, and showing the door of the compartment opened to disclose the interior construction of one form of my invention, 70

Fig. 2 is a top plan view on a reduced scale of the sink associated with the form of my invention depicted in Fig. 1, 75

Fig. 3 is a bottom plan view of the sink and the compartment depicted in Fig. 1,

Fig. 4 is a top plan view of a modified form of sink in which the garbage receptacle is positioned in the center thereof, the drain means being positioned in one corner of said sink, 80

Fig. 5 is a fragmentary sectional detail view of a modified form of closure for the garbage receptacle conveying means, 85

Fig. 6 is a fragmentary cross-sectional view of a still further modified form of my invention,

Fig. 7 is a perspective view of still another form of my invention, 90

Fig. 8 is a somewhat enlarged top plan view of Fig. 7, with the construction slightly modified,

Fig. 9 is an enlarged detail bottom plan view of a suggestive means for associating the garbage conveying means with the bottom of the sink, 95

Fig. 10 is a cross-sectional view of a modified form of compartment in which the garbage receptacle is placed, showing also a means whereby said compartment may be ventilated, and a means for preventing the garbage from freezing, and 100

Fig. 11 is a fragmentary view on an enlarged scale showing a still further modified form of my invention, 105

Describing my invention more in detail, I provide the dwelling or other building D with a compartment constructed of any preferred material, such as wood, iron, brick or the like, and which may form an intimate part of the building, and which, if desired, 110

may be either integral with the sink S, or associated therewith in any manner preferred.

The compartment C has a bottom 1 equipped with a drain means 2 provided with a suitable strainer 3, which drain means may lead to the sewer, and if desired may be equipped with any form of trap, in case the garbage receptacle G is equipped with drainings openings in the bottom thereof. If desired, also, a drain connection 4 may lead from the bottom 1 to the connection 2.

The compartment C has hinged thereto any preferred form of door 5, so that access 15 to the compartment C may be had from the exterior of the building. The top of the door 5, or any portion thereof, may be equipped with a suitable set of ventilating openings 6 covered by a wire screen 7 of very small 20 mesh to prevent any insects or vermin from reaching the compartment C.

Associated with the sink S of a garbage conveying means 8, equipped, if desired, with a cover 9 provided with a suitable 25 handle 10. This garbage conveying means may be rectangular in cross section as disclosed in Fig. 3, or may be cylindrical, as disclosed in certain of the remaining figures, a closure 11 of any preferred type being 30 associated with the bottom thereof, said closure being pivoted as at 12, and equipped at one end with any preferred form of counter balancing means 13, a cord or chain 14, leading to the interior of the building and 35 inclose proximity with the sink, being used to operate the closure 11.

In Fig. 4 the garbage receptacle or conveying means is positioned in the center of the sink S', and is cylindrical in shape, the 40 closure 11' being in the shape of a ball of rubber or other material, a counter balancing means 13' being positioned on the end of the arm 12', which arm is supported in hinged relation as at 15' with the garbage conveying means 8'. In this instance the chain or cord 14 may be omitted or used as preferred. See Fig. 5. In Fig. 4 the drain for the sink is positioned in one of the corners thereof, as indicated at 16', the receptacle or conveying means 8' being equipped with an annular 45 rib or upstanding projection 17' to prevent the sink water from reaching the receptacle 8', though it would not matter if it did, for said water would be conveyed away through 50 the drain 2.

In Fig. 6 I have shown the sink S'' equipped with the usual drain means d'' leading to the sewer, a conventional form of trap t'' being used in said means. The garbage 60 conveying means 8'' in this form of my invention is also cylindrical and is also equipped with an upstanding annular ridge or bead 17'' to prevent the sink water from reaching the receptacle 8''. But it will not 65 matter if said water does reach said recep-

tacle, since a connection c'' to the drain means d'' permits all water to be drawn off to the sewer, except sufficient to form a water seal over the closure 11'', to prevent effectively any odors from the garbage 70 reaching the interior of the building. If desired, the pipe c'' may be provided with a suitable strainer to prevent any solid matter in the garbage reaching the sewer.

In Fig. 6 I have shown also a modified 75 form of closure, formed of a semi-spherical member 11', formed of rubber or other suitable material, the arm 12'' being curved and pivoted within a projection 15'', either integral with the cylindrical member 8'' or 80 associated therewith in any manner preferred, a counter-balance 13'' being associated in any desired manner with the end of the arm 12''. In this case as in the others, a manual means for actuating the closure 85 11'' may be used or omitted.

In Fig. 7 I have shown a still further modified form of my invention. In this case the sink S''' is equipped with a plurality of receptacles 8''' and R''', the garbage being dumped into the receptacle R''', and its liquid content permitted to drain off through the connection c''', equipped with a strainer, to the drain means d''', through the trap t''' to the sewer. As shown in this 90 figure, the bottom of the receptacle R''' is curved, so as to facilitate the removal of the garbage by means of a brush or other device to the receptacle 8''', which conveys the same to a garbage receptacle positioned 95 in the compartment hereinbefore described. In this form of my invention no cover is provided for the receptacle 8''', though one may be used if desired.

In Fig. 8, the sink S'''' is equipped with 105 a drain means d'''', and two receptacles 8'''' and R'''' the bottom of the receptacle 8'''' being provided with a cover 9'''' equipped with a handle 10'''', the receptacle R'''' being used to drain off the liquid content of 110 the garbage as it is deposited therein, the connection c'''' leading to the drain means d'''', as in the other forms of my invention. After the garbage has sufficiently drained 115 within the receptacle R'''', it may be removed therefrom to the receptacle 8'''', from which it is conveyed to the garbage can as hereinbefore described.

In Fig. 9 I have shown a means for associating the cylindrical member 8' with the 120 bottom of the sink, and at the same time provide an efficient means for preventing the water from the sink reaching the compartment C. This means comprises a suitably packed plate 18 encircling the member 8', 125 and associated therewith in any manner desired. The plate 18 is preferably, though not necessarily, rectangular or square in form, and equipped with a set of flanges f and f' four in number, and extending there- 130

from. Said flanges are equipped with holes 19 to accommodate a suitable fastening means in the shape of screws or bolts to fasten the same to the bottom of the sink, the upstanding flange f' being used as a spacing element underneath said sink.

Fig. 10 discloses the compartment C equipped with a means for preventing the garbage from freezing, which means may 10 comprise a pipe 20 connected to the gas piping of the building and leading to a gas fixture providing a gas flame 21. Said compartment may also be equipped with a piping 22 leading from the outer atmosphere 15 below the compartment, and having an extension 23 so as to provide for an efficient circulation of the air through the holes 6 in the door 5, as depicted in Fig. 1. This view also shows the receptacle 8" equipped with 20 a closure 11", similar to that shown in Fig. 6, but provided with a somewhat differently constructed counter balancing means 13". This view also shows a water seal for preventing the odors from compartment C 25 reaching the interior of the building. Any water coming from the garbage can G is drained off through the drain 2 which is here shown as equipped with a sewer trap t".

Fig. 11 shows a still further modified 30 form of my invention in which the sink 24 is equipped with a garbage receptacle 25, provided with a removable strainer 26, and a closure 27 pivoted to the receptacle 25 by a spring means 26, to the side of the receptacle 25, the closure 27 in this case being solid and constructed of any suitable material. A suitable pipe 28 is adapted to carry off the surplus water.

While I have thus described my invention 40 with great particularity, it will be clear that the same may be modified throughout a wide range. I therefore do not propose to be limited to the exact details of construction shown and described, but reserve the right in practice to make any and all modifications 45 thereof that fall within the scope of the appended claims.

I claim as my invention:

1. In an apparatus of the class described, 50 a sink, a garbage receptacle forming a part of and built in said sink, a housing connected to and positioned below said sink and having means external of the building in which said sink is positioned whereby communication

may be had with said housing and a garbage 55 can may be positioned therein below said receptacle, means associated with said sink and said receptacle for draining to the sewer the garbage placed in said receptacle, and means, operable by the weight of said garbage, for depositing said garbage in said garbage can.

2. In an apparatus for conveying garbage to a point accessible from the outside of a building, in combination, a sink, a receptacle 60 in and forming an intimate part of said sink, a compartment secured to said sink, in which a garbage can may be positioned to receive the garbage from said receptacle, means associated with said receptacle and said sink 65 for draining said receptacle to the sewer, and a counter balanced closure for the bottom of said receptacle.

3. In a sink, in combination, a drain therefor, one or more garbage receptacles forming 70 an intimate part of said sink, drain means for draining said receptacles to said drain, and means, operable by the weight of said garbage whereby said garbage may be deposited in a can positioned in a compartment 75 below said sink and accessible only from the exterior of the building in which said sink is positioned.

4. In a sink, in combination, a drain therefor, a garbage receptacle connected to and 80 forming an intimate part of said sink, means associated with said garbage receptacle for preventing the water introduced into said sink from entering said receptacle, a drain 85 means connected to said receptacle and to said sink drain for draining the garbage to the sewer, and a combined closure and water sealing means for the bottom of said receptacle.

5. In a sink, a plural part garbage receptacle forming a permanent part of said sink, drain means for a part of said receptacle connected to the drain of the sink, means connected with another part of said receptacle whereby the garbage positioned in the first 90 part, and after it has been drained positioned in said second part, may be conveyed to a point accessible only from the outside of the building, and a combined water seal and closure for the bottom of said second part.

In testimony whereof I have signed my name to this specification.

HENRY T. McCARTHY.
